UNITED STATES PATENT OFFICE

ARTHUR McLAURIN, OF BOSTON, MASSACHUSETTS

DESIGN FOR A SOFA FRAME OR SIMILAR ARTICLE

Application filed October 27, 1932. Serial No. 45,597. Term of patent 3½ years.

To all whom it may concern:

Be it known that I, ARTHUR McLAURIN, a citizen of the United States, residing at Boston, in the county of Suffolk and State of Massachusetts, have invented a certain new, original, and ornamental Design for a Sofa Frame or Similar Article, of which the following is a specification, reference being had to the accompanying drawing forming a part thereof.

The figure is a perspective view of a sofa frame or similar article, showing my new design.

I claim:—

The ornamental design for a sofa frame or similar article, as shown.

ARTHUR McLAURIN.
